UNITED STATES PATENT OFFICE.

STEPHEN SAMUEL JAMES, OF LONDON, ENGLAND.

CINEMATOGRAPHIC APPARATUS.

Application filed April 22, 1922. Serial No. 556,101.

To all whom it may concern:

Be it known that I, STEPHEN SAMUEL JAMES, a subject of the King of Great Britain, residing at London, England, have 5 invented new and useful Improvements Relating to Cinematographic Apparatus (for which I have filed an application in Great Britain No. 3,798, dated February 1, 1921), of which the following is a specification.

This invention relates to cinematographic apparatus of the kind wherein an endless film is used which can be passed continuously through the optical system of the lantern and thus shown any desired number 15 of times without requiring unwinding and rewinding, the part of the film not in engagement with the projection apparatus being coiled in a roll having its axis vertical 20 on a disc or table which rotates about a vertical axis.

According to my invention, the film as it comes off from the optical system is conducted over roller or other suitable guides 25 to the centre of a coil arranged with its axis vertical and resting on a rotary disc or table, which turns about a vertical axis and which has a conical or convex upper surface, in which radial rollers may be advantageously mounted to support the film with 30 a minimum amount of friction. The upper surface of the rotary disc or table is surrounded by a guard or fence against which the outermost convolution of the coiled film 35 rests, the rotation of the disc or table being in the direction to cause the coiled film to open out or crowd its convolutions together towards the outermost convolution and thus leave a space in the centre to facilitate the introduction into the centre of the 40 coil of the incoming part of the film. This direction of rotation is that which causes the incoming part of the film to be drawn into the coil on the table at its open centre 45 as above mentioned. The part of the film leading off to the optical system, (i. e., the outermost convolution) is conducted away from the coil over the peripheral guard or fence by means of guide rollers or other 50 suitable guides.

The peripheral guard or fence may advantageously consist of a stationary ring or cylinder having on its inner surface one or more grooves or channels with inwardly 55 curved edges, so as to form ball races and in each of such races there is arranged a

row of balls of such size as to project beyond the inner surface of the guard or fence and to reduce the friction between the latter and the outermost convolution of the 60 film. The ball races may be formed of bent tubes slotted around their internal periphery to allow the balls to project. Or if desired the guard or fence may consist of a frame having an annular series of guide rollers on 65 its inner surface.

In the accompanying drawings, I have shown how my said invention may be conveniently and advantageously carried into practice. In these drawings:

Figure 1 is a side elevation.

Figure 2 a side elevation looking in a direction at right angles to that of Figure 1, the rotary disc or table being shown in vertical central section, and

Figure 3 a plan of a cinematograph having my invention applied thereto.

A is a base or frame on which there is mounted a vertical shaft B turning in a bearing C and connected by bevel gearing 80 D, D to an intermediate shaft E, which is driven by chain and sprocket gearing F, G, H from the driving shaft J of the cinematograph. These shafts may moreover be arranged to run on ball bearings. On the 85 shaft B, there is fixed a hub K bearing a conical table L which is provided on its upper surface with a series of radial anti-friction rollers M, M adapted to turn freely between centres on said table.

On the upper end of the shaft B, there is fitted a sleeve N which is capable of being slid off this shaft when desired and is provided at its lower end with a slot adapted to fit over a transverse pin O in the shaft 95 B, so as to provide a driving connection between said shaft and sleeve. In the upper part of this sleeve there slides a radial arm P which is of square or other suitable cross-section and is drawn inwards by means of 100 springs Q, Q attached at their outer ends to hooks on the arm and at their inner ends to hooks on the sleeve N. The lower part of the sleeve is enclosed by a dome R fixed centrally on the table L. The outer part 105 of the radial arm P bears an extension S, which has a roller T that is rotatably mounted on its lower part and is adapted to press against the innermost convolution of the roll of film V resting on the table L. The 110 extension S is preferably fitted friction-tight on the arm P so as to permit of its

being adjusted as required. In order to permit of the roller T passing the part of the film coming in to the interior of the roll from the cinematograph, the arm P is provided with an upstanding pin or projection W, which bears against the peripheral surface of a cam Y formed with an inwardly curved part Y', into which the pin W is drawn by the springs Q, Q when the position of the incoming part of the film V is approached. The cam Y is fixed on an arm Z which is pivotally connected at Z', on the base A and is capable of being sprung in a vertical direction so as to permit of a hole therein being brought into and out of engagement with the upper end N' of the sleeve N. By this means the cam Y can be readily removed and swung to one side to permit removal of the sleeve and attached parts. The film passes down from the cinematograph along a guide 1 of U-shaped cross section, in order to form the innermost convolution of the roll.

The outermost convolution of the roll is retained in position on the rollers M, M by means of an annular guard consisting of a tube 2 secured to the base A and having a circumferential slot 3 in its inner surface, through which extend balls 4, 4 against which the said outermost convolution of the film rests.

The film V returns to the cinematograph over guide rollers 5, 5 mounted on the base A and another 6 adjustably mounted on the cinematograph frame.

The rate at which the film is withdrawn from the roll on the rotary table is controlled by a spring brake 7 consisting of two flat springs pressing towards each other and having leather faces for bearing on the opposite sides of the film. The pressure can be varied e. g., by means of a set screw in one spring bearing against the inner side of the other spring. The position of the brake vertically can be adjusted by sliding it along its supporting post 8 mounted on the base A.

In operation, the film V passes down from the cinematograph mechanism along the U-shaped guide 1 to form the innermost convolution of the roll on the rotary table L which is rotated in the direction of the forward feed of the film on such table. The roll, by reason of such rotation and of the conical form of the table, spreads out so that its outermost convolution rests against the balls 4, 4 in the guard 2, such outermost convolution extending through the brake 7 on its way to one roller 5 whereby it is guided out of the guard 2. From this roller it passes over the other roller 5 and the roller 6 to pass into the cinematograph for projection. The speed of the rotary table L and the degree of pressure exerted by the brake 7 are adjusted as required to produce a regular

feeding of the film. In some cases the roller T, that rotates with the table L and has a smoothing action on the innermost convolution of the film, can be dispensed with.

What I claim is:—

1. A film-winding mechanism for endless cinematograph films, comprising a frame, a table rotatable about a vertical axis and having its surface extending upwardly towards its central part, means for rotating such table, an annular guard arranged around said table and mounted on said frame, and means for conducting the incoming part of the film to the interior of the roll on the table and for conducting the outgoing part of the film away from the exterior of such roll.

2. A film winding mechanism for endless cinematograph films, comprising a frame, a table rotatable about a vertical axis and having its surface extending upwardly towards its central part, means for reducing friction between said table and the edge of the film resting thereon, means for rotating such table, and an annular guard arranged around said table and mounted on said frame.

3. A film winding mechanism for endless cinematograph films, comprising a frame, a table rotatable about a vertical axis on said frame, a series of radial rollers spaced around said table and lying in a conical surface, means for rotating said table, and an annular guard arranged around said table and mounted on said frame.

4. A film winding mechanism for endless cinematograph films, comprising a frame, a table rotatable about a vertical axis and having its surface extending upwardly towards the central part, means for reducing friction between said table and the edge of the film resting thereon, means for rotating said table, an annular guard arranged around said table and mounted on said frame, and means for reducing the friction between the film and such guard.

5. A film winding mechanism for endless cinematograph films, comprising a frame, a table rotatable about a vertical axis and having its surface extending upwardly towards the central part, means for reducing friction between said table and the edge of the film resting thereon, means for rotating said table, an annular guard arranged around said table and mounted on said frame, said guard being provided in its inner surface with a channel having inwardly extending edges, and balls arranged in said channel and projecting beyond the surface of said guard.

6. A film winding mechanism for endless cinematograph films, comprising a frame, a table rotatable about a vertical axis and having its surface extending upwards towards the central part, means for reducing friction between said table and the edge of the film resting thereon, means for rotating

5 said table, an annular guard arranged around said table and mounted on said frame, means for reducing the friction between the film and said guard, and means for conducting the incoming part of the film to the interior of the roll on the table and for conducting the outgoing part of the film away from the exterior of the roll.

10 7. A film winding mechanism for endless cinematograph films, comprising a frame, a table rotatable about a vertical axis and having its surface extending upwards towards the central part, means for rotating said table, an annular guard arranged around said table, an arm mounted on and rotatable with said table, a roller rotatably mounted on said arm and adapted to roll on the innermost convolution of the film, means for pressing said roller against the film, and 15 means for withdrawing said roller from the film when the roller approaches the incoming part of the film.

20 8. A film winding mechanism for endless cinematograph films, comprising a frame, a table rotatable about a vertical axis and having its surface extending upwards towards the central part, means for rotating 25

said table, an annular guard arranged around said table, an arm mounted to slide radially in a guide on said table, a spring 30 acting on said arm to draw it radially inwards, a roller rotatably mounted on said arm, and a cam mounted on said frame and engaging said arm so as to allow it to move periodically inwards.

35 9. A film winding mechanism for endless cinematograph films, comprising a frame, a table rotatable about a vertical axis on said frame, and having its surface extending upwards towards the central part, means 40 for rotating said table, means for reducing the friction between said table and the edge of the film resting thereon, an annular guard arranged around said table, means for reducing friction between said guard and the 45 outermost convolution of the film, and a brake having surfaces for pressing against opposite sides of an outer convolution of the film.

STEPHEN SAMUEL JAMES.
